UNITED STATES PATENT OFFICE.

JOHN C. SCHMIEDER, OF MORSEMORE, NEW JERSEY.

RUCHING-REEL.

No. 926,859.

Specification of Letters Patent.

Patented June 29, 1909.

Application filed February 15, 1909. Serial No. 478,118.

To all whom it may concern:

Be it known that I, JOHN C. SCHMIEDER, a citizen of the United States, residing at Morsemere, county of Bergen, and State of New Jersey, have invented certain new and useful Improvements in Ruching-Reels, of which the following is a specification.

My invention relates to reels for ruchings and the like.

10 The object of my invention is mainly to provide a reel which will be both strong and light, simple and cheap to construct, and handy to use.

15 Reels of this general class commonly comprise two parallel side pieces of card board, joined together by two or more cross-pieces of wood perpendicular to the side pieces and to which the side pieces are nailed. The ruchings are wound upon the two end cross-pieces and confined between the side pieces. In order to stiffen the reel, it has been proposed to extend a card board web of indifferent stiffness between the two side pieces, and secured to the latter by edges bent down 25 parallel to the side pieces. This web being disposed in a plane at right angle to the side pieces, and fixed at one portion in the plane of each side piece and at another portion outside of that plane acts like a truss and is 30 intended to prevent distortion of the reel. The extension of the web across the entire width of the reel has certain disadvantages. It requires a large amount of card board, increases the weight, forms a barrier which 35 prevents pinning through the ruching on the two sides of the reel to fasten the ruching on the reel, and in wide reels does not stiffen the reel as well as it should because the increased width renders buckling easier and thus 40 largely destroys the truss effect.

In accordance with my present invention, all of the above disadvantages are done away with and the objects of the invention attained by the use of an L-shaped strip of card board 45 at each side of the reel extending inward but a relatively short distance from the side pieces. To render this effective, each L-shaped strip is suitably secured, as by adhesive material, to the face of each cross-piece adjacent to one end, and the side pieces are secured by nails which pass through the side pieces and strips into the ends of the cross bars. I thus secure the reinforcing or 50 strengthening strips to the faces of the cross-pieces as distinguished from securing them

to the ends only of the cross-pieces. The construction is thereby stiffer, lighter and more economical, than the old form, and does not prevent pinning through the ruching to fasten the ruching on the reel. While to 60 attain all these advantages it is advisable to have the strengthening strips comparatively narrow, nevertheless my invention also includes securing to the face of the cross-pieces such trussing strips of relatively greater 65 width so long as the strips are centrally spaced or separated. To illustrate the invention, I have shown in the accompanying drawings the preferred specific form.

In said drawings: Figure 1 is an isometric 70 view of a reel in which narrow trussing strips are employed. Fig. 2 is a central longitudinal section of the same, Fig. 3 is a transverse section of the same taken on a line between and parallel to two of the cross pieces, and 75 Fig. 4 is a transverse sectional detail view on a larger scale, taken through a side piece, trussing strip and cross-piece, showing the method of securing the side pieces and trussing pieces to the cross-pieces. 80

Referring now more specifically to said drawing, 10 and 11 indicate the two side pieces, which are suitably secured to cross-pieces 12, 13 and 14 as by nails 15. A strengthening member or strip 16, has a longitudinal portion 16^a, turned up at a right angle and interposed between the side piece 10 and the ends of the cross-pieces 12, 13 and 14, and held by the nails 15 or other means which secure the side piece, and is secured to 85 the face of the cross-pieces 12, 13 and 14 by suitable means such as a layer of adhesive material 17, all as clearly illustrated in Fig. 4 of the drawings. A similar strengthening strip 18 having turned up portion 18^a, is secured in the same manner between the side piece 11 and the ends of the cross-pieces 12, 90 13 and 14, and to the face of the latter. 95

The side pieces 10 and 11 and the strengthening members 16 and 18, are preferably of 100 card board having adequate stiffness, and the cross-pieces 12, 13 and 14 are best constructed of wood. As shown in Figs. 1 and 2 of the drawing, the end cross-pieces 12 and 14 are slightly rounded to more suitably receive the ruching or other material to be wound upon the reel, and the side pieces 10 and 11 extend a suitable distance beyond. 105

It is apparent that the invention is not limited to any particular number of cross- 110

pieces, three being shown merely to serve as an illustration. After the reel has been assembled suitable coverings of paper or other material may be applied to the outer faces of the side pieces over the ends of the nails to improve the appearance, and a layer of this paper or other material may be wound upon the reel for the same purpose without interfering with pinning two or more laps of ruching together between the cross-pieces.

What I claim is:

1. A reel of the character described, comprising in combination a pair of side pieces, a plurality of cross-pieces extending between said side pieces in a plane perpendicular thereto, and a pair of strengthening members fastened to the faces of said cross-pieces and each having a portion turned up at a right

angle and confined between a side piece and the ends of said cross-pieces.

2. A reel of the character described, comprising in combination a pair of card board side pieces, a plurality of wooden cross-pieces, nails securing said side pieces to the ends of said wooden cross-pieces, a pair of card board strengthening strips each having a turned up portion held between the ends of the cross-pieces and a side piece by said nails, and a layer of adhesive material securing said trussing strips on the face of all of said cross-pieces.

JOHN C. SCHMIEDER.
